UNITED STATES PATENT OFFICE.

JOSEPH GRANAT, OF SAN FRANCISCO, CALIFORNIA.

DESIGN FOR A RING.

Application filed July 2, 1924. Serial No. 10,028. Term of patent 3½ years.

To all whom it may concern:

Be it known that I, JOSEPH GRANAT, a citizen of the United States, residing in the city and county of San Francisco and State of California, have invented a new, original, and ornamental Design for a Ring (#1), of which the following is a specification, reference being had to accompanying drawing forming part thereof.

Fig. 1 is top plan view; and

Fig. 2 is an edge elevation of a ring showing my new design.

I claim:

The ornamental design for a ring as shown.

JOSEPH GRANAT.
